METHOD OF AND APPARATUS FOR REFRIGERATION AND AIR CONDITIONING

Laurence S. Harrison, Bronxville, and Allen A. Canton, New York, N. Y., and Alfred G. Kay, Palm Beach, Fla., assignors, by mesne assignments, to said Laurence S. Harrison

Application January 10, 1939, Serial No. 250,142

32 Claims. (Cl. 62—5)

This invention relates to refrigeration and air conditioning, particularly to an air conditioning and cooling system suitable for buses, taxicabs, passenger cars and other mobile or stationary installations which have available waste heat energy and require or are adaptable to use refrigeration or cooled and conditioned air. It is adaptable in enlarged design for air conditioning and refrigeration in buildings equipped with plants operated by Diesel or other types of engines.

The invention utilizes the refrigeration principle of adsorption and compression, the waste heat such as the exhaust of a car furnishing the energy and a suitable adsorbent material such as activated carbon or the like supplying the compression. The invention provides a commercially practical device of light weight, low cost, high relative capacity, mechanical simplicity, reliability, and operating economy.

The adoption of air conditioning in railway transportation has created a definite standard, due to traffic competition, for its application to motor transport of all types. The trend to air conditioning for buses is very well defined and at least one manufacturer of passenger cars has announced that air conditioning in some form will be provided. Once begun, it is believed that public demand will speed the development of air conditioning and will not be satisfied with the present proposals, which amount to little more than improved ventilation, but will require conditioned air in the full sense of the term. This invention supplies this need in that it regulates the temperature of the air, removes its moisture content to a satisfactory extent, and takes care of ventilation requirements.

There are many considerations in the design of an air conditioning system for automobiles, the more important of which are: cost, mechanical limitations, power available, body insulation, available space, added weight, range of climatic conditions, maintenance or operating costs, type of refrigerating material and individual options as to comfort.

It is comparatively an easy matter to design an air conditioning system for the room of a stationary building to meet a relatively stable, average range of conditions. This is not true of a system for mobile units where adequate capacity must be provided for widely varying conditions and choice, with provisions for permissible variation and adjustments to adapt the system to changed conditions or choice.

For automobiles, the major consideration from the standpoint of temperature control is the high temperatures and humidity of summer. The present car heaters take care, to some extent, of low temperature conditions. The humidity created by the respiration of passengers within the relatively small space inside a car body practically avoids the necessity for supplying moisture in winter; but the added humidity due to this 5 cause creates a real problem for applying air cooling and conditioning to a car in summer when the air is already heavily laden with moisture. A study of the daily maximums for a number of scattered cities in the United States indicates 10 that 100° F. dry bulb and 75° F. wet bulb or dew point temperatures may be considered as fair maximum conditions which must be dealt with. It is considered that the equipment must provide 15 a temperature differential of from 10 to 20 degrees for the conditioned air in order for the equipment to be satisfactory. These requirements indicate that relatively high refrigerating capacity must be available under the operator's control. To provide such capacity at low initial 20 cost, light weight, small space occupation and at negligible maintenance cost, is the achievement 25 of this invention.

The relatively small space per occupant in 30 automobiles indicates a very high latent-to-total load ratio, which with the capacities obtainable in this system, may be served by introducing a high percentage of outside air; but actually the total volume required, measured in cubic feet per minute, is very low. From a theoretical consideration of average conditions to be met, it is 35 sufficient to mix re-circulated inside air and fresh outside air in the ratio of 1 to 2 parts respectively; however, the present system is designed to mix re-circulated air and fresh outside air in the 40 ratio of 1 to 1 parts respectively, in order to be on the safe side. Moreover, the capacity of refrigeration is made adequate to reduce the 45 moisture content enough to take care of the high humidity per unit volume produced by respiration. This is done in a simple and economical manner by providing extensive contact between the air and the cooling surfaces, as for example by forcing the air through long passages or labyrinths which give the effect of deep cooling coils.

The cooling unit is designed to discharge from the car a certain amount of used air, for an average passenger car amounting to as much as 20% of the total occupied volume per minute for one 50 passenger, with the ability to increase the per-

centage, on a proportionate basis, up to the total maximum passenger capacity of the car.

Sufficient waste heat from the motor is available to operate the refrigerating equipment, and the use of this waste heat avoids the necessity of either a direct reduction of motive power for driving the car which would be entailed by a compressor system, or the consumption of additional fuel. The manufacturing, installation and operating costs of this system are very much less than they would be with a compressor system and there are few and minor changes required in body design to take care of the refrigerating system. Perhaps the general insulation now provided for deadening sound and the heat insulation at the cowl board behind the motor might have to be increased slightly for best results for air conditioning but the added expense would be slight—and the same for any refrigerating system used.

The enumerated and other objects and features of novelty will be apparent from the description and the drawings.

While the following description is principally directed to the refrigeration of private passenger cars, it will be understood that the invention in principle applies as well to trucks having storage compartments to be refrigerated and also to stationary installations.

The invention will best be understood from a consideration of an exemplary embodiment thereof shown in the accompanying drawings, wherein:

Fig. 1 is a side elevation of a passenger car, partly broken away, equipped with refrigerating or air conditioning apparatus embodying the present invention;

Fig. 2 is a diagrammatic and partly schematic view of the apparatus used on the car shown in Fig. 1;

Fig. 3 is a top plan view of the boiler or generator unit shown in Figs. 1 and 2, the refrigerant connections being omitted for simplicity;

Fig. 4 is an end view taken on the line 4—4 of Fig. 3;

Fig. 5 is a partial sectional view taken on the line 5—5 of Fig. 3;

Fig. 6 is a transverse vertical section through a heat valve, the view being taken approximately on the line 6—6 of Figs. 3 and 7;

Fig. 7 is a longitudinal vertical section taken on the line 7—7 of Fig. 6;

Fig. 8 is a transverse vertical section through a water valve, the view being taken approximately on the line 8—8 of Figs. 3 and 9;

Fig. 9 is a longitudinal vertical section taken on the line 9—9 of Fig. 8;

Fig. 10 is a diagrammatic front end view of the boiler or generator shown in Figs. 1 and 2, showing the refrigerant and water connections;

Fig. 11 is a diagrammatic rear end view looking in the same direction as in Fig. 10;

Fig. 12 is a longitudinal vertical section through one of the boiler units, the view being taken on the line 12—12 of Fig. 3;

Fig. 13 is a transverse vertical section taken on the line 13—13 of Fig. 12;

Fig. 14 is an enlarged transverse vertical section, with certain filling material removed, taken on the line 14—14 of Fig. 12;

Fig. 15 is an exploded view of some of the parts shown in Fig. 14;

Fig. 16 is a view of a detail shown in Fig. 14;

Fig. 17 is a longitudinal vertical section of a condenser shown in Figs. 1 and 2;

Fig. 18 is an end elevation looking at the left end of Fig. 17;

Fig. 19 is a vertical section taken longitudinally of the car, of a heater-cooler unit shown in Figs. 1 and 2;

Fig. 20 is a transverse elevational view taken on the line 20—20 of Fig. 19;

Fig. 21 is a plan view of an air distributing outlet shown in Figs. 1 and 19, the view being taken from the line 21—21 of Figs. 1 and 19;

Fig. 22 is a vertical section taken on the line 22—22 of Fig. 21;

Fig. 23 is a vertical longitudinal section through a valve timer unit shown in Fig. 3, the view being taken approximately on the line 23—23 of Fig. 3; and

Fig. 24 is a transverse vertical section taken on the line 24—24 of Fig. 23.

The system is based upon the adsorption-compression principle of refrigeration, that appearing to be best adapted for automotive purposes because it lends itself to use with apparatus which is simple and inexpensive and not likely to get out of order under rough usage to be expected from various types of roads. Moreover, the invention comprehends the use of an improved type of heat exchange medium which functions properly between the temperature of the motor cooling fluid which is available for cooling it and causing it to adsorb the refrigerant and the temperature of the exhaust combustion gases which are available for heating it and causing it to release the refrigerant. The preferred heat exchange medium and one which has given very satisfactory results in practical tests is activated carbon.

The preferred refrigerant is one which will be adsorbed freely by the adsorbent material at the lower temperatures available, say 120 to 140 degrees F. if engine cooling fluid is employed for cooling the adsorbent material, and which may be in a large measure driven out of or away from the adsorbent material at the higher temperatures available, say 400 to 600 degrees F. if engine exhaust gases at 700 to 900 degrees F. are employed for heating the adsorbent material. Methyl chloride, CH_3Cl , or methylene chloride, CH_2Cl_2 , or what is known commercially as "carrene," have been found to be very satisfactory for employment at this temperature range; and both have the additional advantage of being adsorbed in large volumes by activated carbon. The refrigerant should also be harmless and unobjectionable to passengers in case it should escape. The term adsorbent applies as well to adsorbent materials, though the latter are usually liquids and not preferred for travelling vehicles, although the principles of operation would be similar to those described for solid adsorbent material.

As shown in the drawings, wherein a preferred embodiment of the air conditioning system is applied to a passenger car 20, there is indicated in Fig. 1 an engine exhaust pipe 21 leading to a generator-adsorber 22, a condenser 23, a heater-cooler or heater-evaporator 24, a fresh air inlet 25 leading air to the heater-cooler unit, and a duct 26 leading conditioned air from the heater-cooler unit 24 to an air distributing grill 27 placed at some convenient location in the car. For example, as indicated, the grill may be placed just back of the front seat so that the air will circulate as shown by the arrows. For most efficient operation of the air conditioning system it may be necessary to improve the body insu-

lation somewhat over what is now done for noise and vibration elimination; and it may also be necessary to provide improved insulation at the cowl partition 28 between the motor and the passenger space in the body. As will be seen presently, water from the engine radiator 29 may, in addition to cooling the engine, be used in the air conditioning system, and for this reason it may be necessary to increase the radiator capacity. An increase of approximately 15% is estimated to be entirely sufficient to take care of the air conditioning system.

Normally the car windows will be kept closed while the air conditioning system is operating but this should not require any changes in window operating mechanism in a passenger car or taxicab, although in buses and Diesel operated railway cars it appears advisable to place the operation of windows and all other closures solely under the supervision of the attendant.

In Figs. 19 and 20 the heater-cooler unit 24 and related parts are shown in enlarged section in relation to the familiar parts of the car. Here are shown the cowl partition 28, the fresh air inlet 25, the conditioned air duct 26, the grill 27, the dash 30, the hood 31, the floor 32 and windshield 33. The fresh air inlet 25 is provided with a screen 35 to exclude insects. A plurality of baffle pans 36, 37 separate water from the air and a drain pipe 38 leads water away. An exhaust 30 duct 39 leads outward and backward beneath the floor. If desired, the water pipe 38 may discharge into the duct 39.

Fresh air from the inlet 25 escapes over the edges of the water baffles, as shown by the arrows, and enters a fresh air duct 45 leading to a blower 46 driven by a motor M1. The motor also drives a second blower 47 for recirculating air from the car. The blowers are preferably of the pressure type in order to impart a forced circulation to the air. A strocco type blower is satisfactory. As shown, the blowers 46 and 47 are approximately the same size for handling equal amounts of fresh and recirculated air, although the ratio may be otherwise if desired.

The blower 46 discharges into a duct 48 and the blower 47 discharges into a duct 49. Both ducts 48 and 49 discharge into a mixing chamber 50 which continues in a long flat labyrinth duct 51 passing in a series of loops over cooling coils 52 and heating coils 53. As shown, there are four vertical rows of cooling coils and two vertical rows of heating coils, but it is obvious that the proportion may be varied; and it will be understood that the cooling coils and heating coils may be used alternately or simultaneously as desired. The labyrinth duct gives the effect of deep coils within the limited space available and provides good cooling and moisture elimination which are desirable in a car where the total air capacity is small and the moisture due to respiration is large. A receiver 190 is provided for the cooling coils.

The duct 51 terminates in the conditioned air duct 26 leading to the grill or register 27.

The upper end of the exhaust air duct 39 terminates near the hood and both the fresh air inlet duct 45 and the exhaust air duct 39 may be provided with valves 57 and 58 respectively. The valves may be of the butterfly type and both may be mounted on a shaft 59 provided with an operating arm 60 and an operating rod 61 controlled from the dash. Positive pressure created inside the body by conditioned air causes exhaust air to leave by way of the duct 39.

There will be as much air leaving by the exhaust duct 39 as there is fresh air being drawn in by the fresh air duct 45. The valve 57 is provided to cut off or reduce the supply of fresh air, particularly when larger quantities of inside air are being recirculated or when the system is inoperative and natural draft ventilation is used. The valve 58 is provided to prevent the entry of engine exhaust gases when a suction toward the inside of the car exists.

A switch 62 may be associated with the rod 61 for causing the blower motor M1 to operate when the valves 57 and 58 are open and to stop when the valves are closed.

As shown in Figs. 21 and 22 the duct 26 terminates in a distributor 63 which divides the air into a lower channel 64 having outlets 65 and 66 and an upper channel 67 having outlets 68 and 69. By this arrangement a wide distribution of the conditioned air is obtained at the grill 27.

The cooling coils 52 and the heating coils 53 may be provided with fins 70 having good thermal conductivity.

The duct 51 where it joins the duct 26 may be provided with a low dam 71 and behind this with a drip pipe 72 for leading condensate from the evaporator coils to the drip pipe 38.

Referring to Fig. 2, which is a diagrammatic and partly schematic view of the apparatus, the parts already described will be identified and then other parts will be described. Here are found the engine exhaust pipe 21; the generator-adsorber 22, the condenser 23, the heater-cooler or heater-evaporator unit 24, the engine radiator 29, blower motor M1, and dash switch 62. The engine is designated by the numeral 75, the generator as 76, the battery as 77, the water pump as 78 and the exhaust tail pipe as 79. The water circulation system for the engine 75 is generally indicated by the numeral 80 and this is provided with a throttle valve 81 for proportioning the flow of cooling fluid between the engine and the air conditioning system.

Cooling fluid flows to the condenser 23 by way of an inlet pipe 82 and away from the condenser by an outlet pipe 83 which finally joins a radiator return pipe 84.

The generator-adsorber 22 may be cooled by air or by an independent air-water cooling system, but preferably it is cooled by fluid from the engine cooling system, as shown. Cooling fluid may flow to the boiler or generator by way of an inlet pipe 87 and out by an outlet pipe 88. Another outlet pipe 89, which may be referred to as the backpass outlet, may be provided for more positively evacuating the cooling fluid from the boiler at times, as will be later explained. The pipe 89 may be provided with a back-pass suction pump 90 driven for convenience by a pump-timer motor M2, although the pump may be driven directly by the engine. A check valve 91 is placed in the pipe 89 to prevent flow in a direction other than that indicated by the arrow. The motor M2 may be controlled by a dash switch 92 and a rheostat R.

The heater-evaporator is supplied with hot fluid from the engine cooling system when desired by an inlet pipe 93 equipped with a cut-off valve 94. Cooling fluid, i. e. hot water, leaves the heater-evaporator by way of the outlet pipe 95.

Besides driving the pump 90 the motor M2 also drives a valve timer 100 which in turn drives a valve operating shaft 101 at the boiler through a flexible shaft 102.

Refrigerating fluid may flow from the generator-adsorber 22 to the condenser 23 through the pipe 103; from the condenser to the evaporator 24 through the pipe 104; and from the evaporator back to the boiler through the pipe 105. The flow of refrigerating fluid divides at the generator-adsorber 22 between a plurality of generator-adsorber units 22A, 22B, 22C, and 22D by way of the pipes 105A, 105B, 105C, 105D, 103A, 103B, 103C, and 103D. Check valves 106 and 107 are provided for preventing back flow.

As the refrigerating fluid is divided between the four generator-adsorber units A, B, C and D, so also are the exhaust gases from the exhaust pipe 21 divided between the four units. This is also true of cooling fluid from the inlet pipe 87. But whereas the refrigerating fluid is permitted to divide according to conditions existing within the generator-adsorber units, the exhaust gases are controllably divided by an exhaust or heat valve 108; and the cooling fluid is divided by the water valves 109 and 110. All of the valves 108, 109 and 110 are driven by the drive shaft 101.

In Figs. 3, 4 and 5, the generator-adsorber and associated parts, with the exception of the refrigerant system, are shown on an enlarged scale. In Fig. 3 the four units 22A, 22B, 22C, 22D are shown as being supplied with heating gases from the exhaust pipe 21 and valve 108 by four branch exhaust pipes 21A, 21B, 21C and 21D; and the used heating gases are passed to the exhaust tail pipe 79 by the four branch pipes 79A, 79B, 79C and 79D. A muffler 111 may be provided, if desired, but this may be small or even omitted since the boiler units provide a muffling effect.

The water valves 109 and 110, conveniently, may be placed below the generator-adsorber, as shown in Figs. 4 and 5, and be driven by shafts 112 through gear sets 113 at each end.

In Figs. 3 and 4, the water inlet pipes 87A, 87B, 87C and 87D from valve 109 are shown at the front end of the generator-adsorber and in Fig. 3 the water outlet pipes 88A, 88B, 88C and 88D are shown. It will be noted that the shafts 101 and 112 rotate in the same direction and at the same speed in order to keep the valves 109 and 110 in step with the valve 108.

In Figs. 6 and 7 the exhaust or heat valve 108 is shown in enlarged detail. Here it is seen that the shaft 101 drives a valve body 118 which rotates within the casing of the valve. Preferably the valve body 118 is formed of a vitreous or other heat and corrosion resistant material operating in hard molded graphite bearings 119, 120. The valve body 118 is provided with an elongated arcuate port 121 which partly spans two of the branch openings 21A, 21B, 21C or 21D in passing from one to the other. This is of value to prevent undue back pressure on the engine during transfer of the valve opening from one unit to the next, and when the system is shut down, as will be later explained. The valve casing is made in separable parts to permit easy repair or replacement.

In Figs. 8 and 9 the front water valve 109 is shown in enlarged detail. Here it is seen that the shaft 112 drives a valve body 124 within the casing of the valve. The valve body 124 is provided with a short arcuate through port 125 and a long arcuate through port 126. The short port 125 will partly cover two adjacent branch openings 87A, 87B, 87C or 87D and the long port 126 will partly cover three openings, for a reason

which will be later explained. The valve body 124 is also provided with a back-pass port 127 extending through the front in position to cooperate with the branch openings 87A, 87B, 87C, 87D and extending through the periphery in position to cooperate with the fixed ports 128A, 128B, 128C, 128D formed in a port ring 128. The port 127 does not extend straight through the valve body as do the ports 125 and 126. The fixed ports 128A, 128B, 128C and 128D open into an annular back-pass chamber 129 which communicates with an opening 130 connecting with the back-pass pipe 89 of the pump 90.

The valve 110 is identical with the valve 109 with the exception that the opening 130 of 110 is disposed at the top and admits air instead of being at the bottom for exhausting water. The valve bodies of both valves 109 and 110 are exactly in phase. Strainers S are provided for the valves 109, 110.

It is provided that the valves in normal operation will pause at the ports and move rapidly between ports. The mechanism for accomplishing this is shown in Figs. 23 and 24 and will be described later. The action of the valves may be followed by observing Figs. 6-9. Figs. 6 and 7 show the port 121 over the opening 21C for supplying exhaust heating gases to the generator-adsorber unit 22C. Figs. 8 and 9 show the port 125 over the opening 87D and the port 126 over the openings 87A and 87B for supplying cooling fluid to the units 22A, 22B and 22D. The port 127 is positioned over the opening 128C at both ends of the generator-adsorber whereby water is positively withdrawn from unit 22C at the bottom front end at opening 130, and outside air is at the same time drawn in at the top rear end. That is, while three units 22A, 22B, and 22D are being cooled, the other unit 22C is being heated and the residue of water is being withdrawn by the back-pass pump while fresh air is being drawn in to replace the water. This cycle is maintained continuously, three units being cooled while one unit is being heated. For example, if each unit is heated for 20 seconds it will be cooled for 60 seconds in a total cycle period of 80 seconds.

Figs. 10 and 11 illustrate this in a readily understandable manner. In Fig. 10 the pipes 87A, 87B and 87D are shown to be supplying cooling water to the generator-adsorber units 22A, 22B and 22D, while the pipe 87C is shown to be empty to denote that the water has been withdrawn by the back-pass pump from the unit 22C and that air is being drawn through it in reverse direction while it is being heated.

In Fig. 11 heated water is shown as being withdrawn from the generator-adsorber units 22A, 22B and 22D by the pipes 88A, 88B and 88D, while air is being supplied by the pipe 88C to the unit 22C which is being heated. The arrows alongside the pipes 105A, 105B and 105D in Fig. 10 indicate that refrigerant is being adsorbed into the units 22A, 22B and 22D which are being cooled; while the arrow alongside the pipe 103C in Fig. 11 indicates that refrigerant is being driven out of the unit 22C which is being heated.

The condenser 23 is shown in enlarged detail in Figs. 17 and 18. Here it is seen that the condenser in a preferred embodiment, comprises an outer casing 134 and an inner casing 135 secured together at one end and spaced apart at the other end. An outer coil 136 for refrigerant is placed in the annular space between the casings 134 and 135 and an inner coil 137 for refrigerant

is placed within the inner casing. The coils are connected around the end of the inner casing. Refrigerant enters the outer coil 136 from the pipe 103 and leaves the inner coil 137 through the pipe 104. Cooling fluid enters the inner casing from the central pipe 82 and leaves by the two outer pipes 83a and 83b connected to the pipe 83 shown in Fig. 2. This arrangement makes a very effective heat exchange arrangement between the refrigerant and the cooling fluid.

Figs. 12-16 show a preferred construction of a unit for the generator-adsorber 22. The construction is the same for all of the four units so general reference characters applying to the generator-adsorber as a whole will be used. Here it is seen that exhaust gases enter by the pipe 21 and leave by the pipe 79; that refrigerant enters by the pipe 105 and leaves by the pipe 103; and that cooling fluid enters by the pipes 87a, 87b and 87c and leaves by the pipes 88a, 88b, 88c. It will be noted that the pipes 87a, 88b and 88a, 88b are disposed on the side of the unit while the pipe 87c is disposed at the bottom for draining water at times and the pipe 88c is disposed at the top for admitting air at times.

If desired, the side pipes 87a, 87b, 88a, 88b may be dispensed with and only the pipes 87c and 88c used. In this case water enters by the pipe 87c at the bottom, rises as heated, and leaves by the pipe 88c at the top. Then when the port 127 of the valve 109 opens the pipe 87c to the back-pass pump and the port 127 of the valve 110 opens the pipe 88c to the air, the air enters at the top and the water can be completely driven out at the other end (front) at the bottom. However, the use of several water pipes may be desirable because they provide a very rapid flow and good distribution through the unit.

If desired, also the valve 110 which admits air may be placed above the boiler instead of below, as shown, to prevent flow of water out the air port when opened. However, the suction of the back-pass pump will normally prevent this.

The exhaust gases between the pipes 21 and 79 pass through the unit in a multi-lobed (five lobes shown) "fire" tube 140 provided with inclined baffle plates 141 in the lobes for directing gases outwardly.

Around the fire tube 140 there are placed a number of copper partition fins 142 between which is disposed the adsorbent material such as activated carbon 143, the latter being indicated by stippling. The fins may be provided with bent tabs 142a for holding them straight and spacing them the proper distance apart. For activated carbon a satisfactory spacing may be 8 fins to the inch, in order to provide a reduced time rate of heat transfer to the carbon granules by providing a high degree of metal mass dispersed in the mass of carbon to be heated and cooled.

It should be noted that while the carbon granules filling the cells between the metal fins may be compacted to a considerable extent, the preferred arrangement is to provide firm packing of the granules to prevent looseness or movement from vibration and at the same time give a good filtering access for the refrigerant to the pores of its adsorbent.

The shape of these fins is shown in Fig. 15. Here the tabs 142a are shown before they are bent.

The fins are provided with cut out portions 144 at the top and bottom, having overhanging portions 145. Two thin sheet copper covers 146 snap into place upon all of the spaced fins to-

gether, the curved edges 147 of the covers engaging the overhanging portions 145 of the fins.

Perforated copper strips 148 slide endwise into the openings 144 beneath the overhanging portions 145. The use of the sliding strips 148 permits the complete filling up of all space between the fins 142 with 10 to 18 mesh activated carbon.

The entire assembly is enclosed by an imperforate copper cartridge 150 welded to the end 10 plates of the boiler unit. The spaces between the perforated strips 148 and the cartridge 150 form conduits extending the entire length of the unit for passage of refrigerant; and the perforations of the strips permit the penetration or escape of refrigerant to and from the adsorbent material at any point along the length. If desired, the elongated spaces may be made of gradually decreasing or increasing size for the entering or escaping refrigerant to take care of decreasing or increasing amounts passing any given section. The refrigerant intake pipe 105 is connected with the upper space and the outlet pipe 103 is connected with the lower space as shown in Fig. 12.

Between the cartridge 150 and the outer casing 151 of the unit there are disposed a plurality of heat conducting fins 152 of a material such as copper. These fins have spacing tabs 153 fitting upon the cartridge 150 and increasing the contact area therewith. The pipes 87a, 87b and 87c 25 may extend through the fins 152 from one end of the unit to the other and between fins may be provided with holes in the side for distributing water to the spaces between the fins. The outlet pipes 88a, 88b and 88c may also extend through all of the fins and be provided with holes 30 in the sides for collecting water between fins.

Each generator-adsorber assembly unit is insulated by porcelain spacers 154 and the four units are bolted between two bracket flanges 155, 40 one at each end, providing means for securing and mounting the entire adsorber-compressor. The units are readily removable for replacement or repair.

A preferred form of valve operating and timing means will now be described by reference to Figs. 23 and 24. But first it is to be noted from Fig. 2 that the pump-timer motor M2 is controlled jointly by a dash switch 92 and a timer switch 158, the switches being in parallel so that the motor will continue to run even after the dash switch 92 is opened until the switch 158 in the timer 100 is also opened. Of course, in starting, the motor will begin operating when the switch 158 is open if the dash switch 92 is closed. This arrangement is one means for insuring that no boiler unit will be exposed to the continued heat of exhaust gases for a long period without at the same time also furnishing cooling fluid to the unit to prevent injury. The particular method of accomplishing this is to move the valves to mid-position between normal halting positions, that is, to move the valves 45 degrees before the motor is finally cut off after the dash switch 92 is opened.

It may be seen from Fig. 6 that when the valve body 118 is stopped in the mid-position, i. e., 45 degrees beyond its normal halting position illustrated, the elongated port 121 will partly span and supply exhaust gases to two pipes, for example, the pipes 21C and 21D.

It may also be seen from Fig. 8 that when the valve body 124 is stopped in the mid-position, i. e., 45 degrees beyond its normal halting position illustrated, the elongated port 125 will partly span and supply cooling fluid to two pipes, for

example the pipes 87D and 87A; while the elongated port 126 will also span and supply cooling fluid to two pipes, for example, the pipes 87B and 87C. The port 127 will be closed. The result will be that cooling fluid will be supplied to all four units while exhaust gases are supplied to two units, and the air inlet is not open to any unit. The purpose of having the ports 127 closed is to prevent the spilling of cooling fluid out the air intake opening when the back-pass suction pump is inoperative.

With this preliminary explanation the construction and operation of the timer mechanism shown in Figs. 23 and 24 may be understood.

The motor shaft 159, through a train of reducing gears housed by a casing 160, drives a gear 161 which, through a gear 162, drives a Geneva pin shaft 163. The shaft 163 carries fast thereon a pin arm 164 provided with a pin 165. A roller may be mounted on the pin 165 if desired. A Geneva disk 166 carrying the slots 167 is mounted on a shaft 168 in position to cooperate with the pin 165. The shaft 168 drives the flexible shaft 102 previously mentioned. Each time the shaft 163 rotates, the pin 165 rotates the Geneva disk 166 through 90 degrees and four turns of the shaft 163 will rotate the Geneva disk four spaces, corresponding to the four boiler units and the four fixed ports or pipes of the exhaust gas and cooling fluid valves.

A locking arm 171, provided with a detent pin 172 adapted to enter the slots of the Geneva disk 166, is mounted on a fixed pivot pin 173 above and to one side of the shafts 163 and 168. Near its mid-length and upon a spur arm 174 the locking arm 171 carries a cam pin 175 adapted to cooperate with a cam 176 carried by the shaft 163. The cam 176 is disposed at such an angle to the pin arm 164 as to raise the detent pin 172 away from the disk 166 when the disk is being turned by the pin 165. A spring 177 pulls cam pin 175 against the cam 176 and the detent pin 172 toward the Geneva disk 166.

Means are provided for operating the switch 153 from the locking arm 171. For example, an arm 180 is loosely mounted on the pivot pin 173 and extends out between spaced pins 181, 182 carried by the arm 171. At its outer end the arm 180 carries a pin 183 operating in the slot 184 of a switch operating lever 185 pivoted upon a stud 186. At its free end the lever 185 carries a switch operating pin 187 adapted to engage the upper protruding blade of the switch 158 to separate the contacts. A spring 188 secured to the stud 186 at one end and to the pin 183 at the other end serves to impart a snap action to the lever 185 when passing over dead center position.

From this it will be clear that when the cam pin 175 rolls up on the high point of the cam 176 while the Geneva pin is in its mid-operating position, that is in a line joining the centers of shafts 163 and 168, it will cause the arms 171 and 180 to actuate the switch lever 185 in a direction to open the switch 158. This will immediately stop the motor if the switch 92 has already been opened. If the switch 92 has not been opened the motor will continue its normal operation and the Geneva pin 165 will carry the Geneva disk through the full 90 degree turn and leave it in the position shown in Fig. 23.

The operation of the apparatus is believed to be clear from the foregoing description. The exhaust gases pass through the generator-adsorber units at all times. At such times as the

system is inoperative the exhaust gas valve is open sufficiently to prevent undue back pressure on the engine. Also, as previously pointed out, the valve port always spans two openings in passing from one to another to prevent undue back pressure. The valve can never stop in a position to completely block the exhaust gases and prevent operation of the motor.

Through the switch 62 the operator has complete control of the motor M1 and the fans of the heater-cooler 24; through the rod 61 he has control over the valves 57 and 58 for the fresh air and exhaust air; and through the switch 92 and the rheostat R he has control of the timer motor M2 and through it of the boiler operation. Other controls, such as the valve 94 for the heating coils 53, may be located within easy access to the operator. Likewise, the valve 81 for proportioning the engine cooling fluid between the engine and the air conditioning system may be placed where readily accessible.

The air conditioning system herein described imposes but little burden on present facilities, either as to power requirements or as to weight. The generator-adsorber unit actually utilizes in a practical manner the heat of exhaust gases which heretofore has been lost. Indeed it is one of the important features of this invention that it employs waste heat in a simple and convenient manner to produce refrigeration, and this will be true whether the waste heat is derived from internal combustion engines or from other sources. And the weight and size of the apparatus are negligible factors as may be illustrated by the following practical example for use with automotive vehicles.

Adsorptive material, such as activated carbon, is available in the open market, having an adsorptive capacity for methyl chloride (CH_3Cl) of over 30% of the weight of the adsorptive material between temperature limits of 125° F. and 450° F. and at pressures, respectively, of 27.9 pounds per square inch (suction) and 150 pounds per square inch (head), which are the expected maximum conditions existing in such an air conditioning system. For methylene chloride (CH_2Cl_2) the adsorptive capacity would be over 33% of its weight between the same temperature limits and at respective pressures of 22.63" of vacuum (suction) and 6.56 pounds per square inch (head).

With 1.345 pounds of methyl chloride required per minute for each ton of refrigeration, or 1.492 pounds of methylene chloride either refrigerant 55 would require approximately 4.5 pounds of carbon per ton of refrigeration. With the proposed design, each boiler or heat transfer unit would contain 1.5 pounds of carbon for each ton of refrigeration. Practical tests indicate that $\frac{1}{2}$ ton of refrigeration is ample to air condition the average private passenger automobile.

This would require but .75 pound of carbon per boiler, and this mass of adsorbent material with the design of the container proposed may be heated to 500° F. in 15 seconds by exhaust gases at 700° F. The twenty seconds heating cycle is therefore adequate to drive the gas to the necessary compression in a container of $2\frac{1}{2}$ " diameter and $15\frac{1}{4}$ " long. The entire heat transfer assembly can hence be mounted conveniently underneath any standard make of automobile, and may take but little more space than the conventional muffler, which can be dispensed with when the present system is used.

The proportions mentioned are believed to be

most satisfactory for the lighter weight vehicles; but for the heavier vehicles or stationary installations where waste heat is available it is possible to construct larger and heavier units to take care of almost unlimited capacity.

It is thus seen that the present invention provides improved practical apparatus and method of refrigerating and conditioning air and is particularly suited for the needs of automotive vehicles. And while one embodiment has been illustrated and described with particularity, it will be understood that the invention may have various embodiments within the limits of the prior art and the scope of the subjoined claims.

We claim:

1. An air conditioning system for automotive vehicles driven by internal combustion engines, comprising in combination, a generator-adsorber provided with a plurality of generator-adsorber units containing a refrigerant adsorbent material, means for selectively passing hot exhaust gases from the motor to said units to drive the refrigerant out of said adsorbent material, a condenser receiving said refrigerant from successive units, means for selectively passing engine cooling fluid to said units which are not being heated to cause the material to adsorb refrigerant, an evaporator receiving refrigerant from said condenser, and means for supplying refrigerant from said evaporator to said units.

2. An air conditioning system for automotive vehicles driven by internal combustion engines, comprising in combination, a generator-adsorber provided with a plurality of generator-adsorber units containing a refrigerant adsorbent material, means for selectively passing hot exhaust gases from the motor to said units to drive the refrigerant out of said adsorbent material, a condenser receiving said refrigerant from successive units, means for passing engine cooling fluid to said condenser, means for selectively passing engine cooling fluid to said units which are not being heated to cause the material to adsorb refrigerant, an evaporator receiving refrigerant from said condenser, and means for supplying refrigerant from said evaporator to said units.

3. An air conditioning system for automotive vehicles driven by internal combustion engines, comprising in combination, a generator-adsorber provided with a plurality of generator-adsorber units containing a refrigerant adsorbent material, means for selectively passing hot exhaust gases from the motor to said units to drive the refrigerant out of said adsorbent material, a condenser receiving said refrigerant from successive units, means for selectively passing engine cooling fluid to said units which are not being heated to cause the material to adsorb refrigerant, means for selectively exhausting engine cooling fluid from said units after the supply of cooling fluid is cut off and drawing air through the exhausted unit, an evaporator receiving refrigerant from said condenser, and means for supplying refrigerant from said evaporator to said units.

4. A heat exchange device, comprising in combination, a plurality of units each provided with a chamber containing refrigerant adsorbent material, means for leading refrigerant to said chambers from an evaporator, means for conducting refrigerant from said chambers to a condenser, a heating fluid chamber for each unit, a cooling fluid chamber for each unit separate from said heating fluid chamber, and means for alternately admitting heating fluid and cooling fluid to the heating and cooling chambers of said

units in rotation, said last mentioned means including an intake valve for the heating fluid and intake and exhaust valves for the cooling fluid, all of said valves being synchronized.

5. A heat exchange device, comprising in combination, a plurality of units each of which is provided with separate chambers for heating fluid, for cooling fluid, and for activation fluid subject to change of condition with heat treatment, means for supplying and removing the activation fluid from all units as required by the treatment, and means for alternately admitting heating fluid and cooling fluid to the heating and cooling chambers respectively of said units in rotation, said last mentioned means including separate valves for said heating fluid, for said cooling fluid, and for said activation fluid.

6. A heat exchange device, comprising in combination, a plurality of units each of which is provided with separate chambers for heating fluid, for cooling fluid, and for fluid activation material, means for supplying and removing an activation fluid to and from all of the chambers containing fluid activation material as required by the treatment, and means for alternately admitting heating fluid and cooling fluid to the heating and cooling chambers of said units in rotation, said last mentioned means including an intake valve for the heating fluid and intake and exhaust valves for the cooling fluid, all of said valves being synchronized.

7. A refrigerating system adapted to be operated as an auxiliary to an internal combustion engine, comprising in combination, an evaporator, a condenser, a heat exchanger containing adsorbent material of a type which adsorbs and releases refrigerating fluid between the temperatures of engine cooling water and exhaust gases, the refrigerating fluid being of a type which is capable of adsorption by and release from the material between the same temperatures, and means for selectively heat treating said material in the presence of refrigerating fluid but without contact with the material or refrigerating fluid with exhaust gases and cooling water, said last mentioned means including separate synchronized control means for said exhaust gases and said cooling water.

8. The method of operating a refrigerating system as an auxiliary of an internal combustion engine, which comprises, alternately condensing and expanding a refrigerating fluid in a suitable medium by alternately changing the temperature of the medium in the presence of the refrigerating fluid by treatment first with engine cooling water to approximate the temperature of the water and then with hot exhaust combustion gases to approximate the temperature of the hot gases.

9. A heat exchange system of the adsorbent type, comprising in combination, a plurality of heat exchange units containing adsorbent material for alternately adsorbing and releasing refrigerating fluid with change in temperature, means including distinct and separately though coordinately controlled heating fluid and cooling fluid for selectively heating one unit while cooling another unit, said heating and cooling fluids being kept separate from said adsorbent material and refrigerating fluid, and constantly operating means actuated independently of the condition of said refrigerating fluid for controlling the flow of the heating and cooling fluids.

10. A heat exchange system of the adsorbent type, comprising in combination, a plurality of

heat exchange units containing adsorbent material for alternately adsorbing and releasing refrigerating fluid with change in temperature, and means for simultaneously heating and cooling a single unit in the inoperative condition of the system. 5

11. A heat exchange system of the adsorbent type, comprising in combination, a plurality of heat exchange units containing adsorbent material for alternately adsorbing and releasing refrigerating fluid with change in temperature, means for selectively heating one unit while cooling another, and means for simultaneously heating and cooling a single unit in the inoperative condition of the system. 10

12. A heat exchange system of the adsorbent type, comprising in combination, a plurality of heat exchange units containing adsorbent material for alternately adsorbing and releasing refrigerating fluid, means for selectively heating one unit while cooling another during normal operation, means for simultaneously heating and cooling a single unit in the inoperative condition of the system, and means controlling the timing of said heating and cooling means during normal operation which automatically stops in position to cause the simultaneous heating and cooling of a single unit in the inoperative position. 15

13. A heat exchange system, comprising in combination, a plurality of stationary heat exchange units each provided with separate compartments for refrigerating fluid, for heating fluid, and for cooling fluid, valve means for controlling in rotation the flow of heating and cooling fluid to said units, and means for controlling said valve means for causing it to simultaneously supply heating and cooling fluid to a single unit in the inoperative condition of said system. 20

14. Apparatus as set forth in claim 13 further characterized by the fact that said controlling means contains elements which cause the valve means to automatically halt in the position to supply both heating and cooling fluid to a single unit when the operator turns off the system. 25

15. A heat exchange system comprising in combination, a heat exchange unit provided with separate compartments for an adsorbent material and refrigerating fluid, for heating fluid, and for cooling fluid, valve means for alternately supplying cooling fluid and heating fluid to said unit, and means associated with said valve means for admitting air to the cooling fluid compartment when heating fluid is admitted to said heating fluid compartment. 30

16. A heat exchange system, comprising in combination, a heat exchange unit provided with separate compartments for activated carbon and a refrigerating fluid, for exhaust heating gases, and for cooling water, synchronized valve means for alternately supplying exhaust heating gases and cooling water to said unit, and means associated with said valve means for admitting air and sucking water out of the water compartment when exhaust heating gases are admitted to said heating compartment. 35

17. Apparatus as set forth in claim 16, further comprising in combination, means for shutting off air and causing both heating fluid and cooling fluid to flow to said unit simultaneously when a predetermined condition exists in the system. 40

18. A heat exchange system, comprising in combination, a heat exchange unit provided with separate compartments for adsorbent material and refrigerating fluid, for heating fluid, and for cooling water, means for controlling the flow 45

of water to the water compartment, means for withdrawing substantially all the water from said compartment at regulated times, and means for preventing the backflow of water to said compartment when withdrawn. 50

19. Apparatus of the character described, comprising in combination, a plurality of refrigerating units, and synchronized intake and exhaust valves serving said units, said valves having means for supplying and exhausting one fluid to and from one of said units, and for exhausting said fluid in reverse direction and supplying a chaser fluid to another unit. 55

20. Apparatus of the character described, comprising in combination, a plurality of removable heat exchanger units, said units having separate compartments for refrigerating fluid, for exhaust heating gases, and for cooling fluid, metal supports for said units, and heat insulating means between said units and said metal supports, said means providing for the passage therethrough of exhaust gases. 60

21. Apparatus of the character described, comprising in combination, a heat exchange unit having separate compartments for refrigerating fluid and an adsorbent material, for cooling fluid, and for exhaust heating gases, a multilobed central conduit for said exhaust gases, spaced metal partitions on said central conduit forming cells for adsorbent material, means for supplying refrigerating fluid at the bottom and withdrawing it at the top of said cells along the length of said unit, spaced metal partitions in said cooling fluid compartment which is located outside around said refrigerating compartment, and means for supplying cooling fluid at the bottom and withdrawing it at the top of said cooling compartment along the length of said unit. 65

22. Apparatus of the character described, comprising in combination, a heat exchanger having compartments for refrigerating fluid, for heating fluid, and for cooling fluid, valve means for controlling the flow of heating fluid and cooling fluid to said heat exchanger, means for timing the operation of said valve means independently of the heating or cooling effected, and means for varying the speed of said valve timing means. 70

23. Apparatus as set forth in claim 22 wherein said timer is driven by an electric motor and said speed varying means comprises a rheostat under the supervision of an operator. 75

24. Apparatus of the character described, comprising in combination, a heat exchanger having compartments for refrigerating fluid, for heating fluid, and for cooling fluid, valve means for controlling the flow of heating fluid and cooling fluid to said heat exchanger, a timer for operating said valve means, said timer including a quick throw motion for operating said valves to normal positions, and means, including switch operating means for stopping said valves in a mid position when said timer is stopped. 80

25. Apparatus as set forth in claim 24 in which said switch operating means includes a snap-over member operated by a member moving in unison with valve operating means. 85

26. Air conditioning apparatus for automotive vehicles, comprising in combination, a heat exchanger, means including a motor and fan for forcing air into said vehicle through said heat exchanger, an exhaust duct for leading used air out of said vehicle through the floor, a valve in said exhaust duct, a dash switch for said fan motor, and an operating member for said switch, said member also being associated with said 90

valve to close it when the motor is rendered inoperative.

27. Air conditioning apparatus for automotive vehicles, comprising in combination, a heat exchanger inside the vehicle, means including a fan and motor for forcing air into said vehicle through said heat exchanger, an exhaust duct for leading used air out of said vehicle under static pressure created by fresh air intake, and a parallel connected valve control for conjointly regulating the intake of air to said fan and the outflow of gas through said exhaust duct.

28. Apparatus for producing refrigeration from the waste heat of combustion, comprising in combination, means for admitting to portions of adsorbent activated carbon a refrigerating fluid which is capable of being adsorbed in substantial quantities by activated carbon at temperatures of engine cooling fluid and which is driven off without injury at temperatures approximating the temperatures of engine exhaust gases, means for circulating engine cooling fluid at times in good heat exchanging relation to but not in contact with the carbon for causing the adsorbing action, and means for alternatively circulating engine exhaust gases in good heat exchanging relation to but not in contact with the carbon for heating the carbon at times to drive off the adsorbed refrigerating fluid.

29. The method of producing refrigeration from heat, such as the waste heat of combustion, which comprises, admitting to portions of adsorbent activated carbon a refrigerating fluid which is capable of being adsorbed in substantial quantities by activated carbon at temperatures of engine cooling fluid and which is driven off without injury at temperatures approximating the temperatures of engine exhaust gases, circulating engine cooling fluid at times in good heat exchanging relation to but not in contact with the carbon for causing the adsorbing action, and alternatively circulating engine exhaust gases in good heat exchanging relation to but not in contact with the carbon for heating the carbon at times to drive off the adsorbed refrigerating fluid.

30. Apparatus for producing refrigeration from the waste heat of combustion of an internal combustion engine, comprising in combination,

heat exchange means containing a non-liquid porous refrigerant adsorbent material which is stable and effective at the temperatures of engine cooling fluid and engine exhaust gases, means for admitting to portions of the adsorbent material a refrigerating fluid which is capable of being adsorbed in substantial quantities by the adsorbent material at the temperatures of engine cooling fluid and which is driven off without injury at temperatures approximating the temperatures of engine exhaust gases, means for circulating engine cooling fluid at times in good heat exchanging relation to but not in contact with the adsorbent material for causing the adsorbent action and means for alternatively circulating engine exhaust gases in good heat exchanging relation to but not in contact with the adsorbent material for heating the material at times to drive off the adsorbed refrigerating fluid.

31. The method of producing refrigeration from the waste heat of combustion of an internal combustion engine, and comprises; admitting to portions of a non-liquid porous refrigerant adsorbent material, which is stable and effective at the temperatures of engine cooling fluid and engine exhaust gases, a refrigerating fluid which is capable of being adsorbed in substantial quantities by the adsorbent material at the temperatures approximating the temperatures of engine exhaust gases; circulating engine cooling fluid at times in good heat exchanging relation to but not in contact with the adsorbent material for causing the adsorbent action; and alternatively circulating engine exhaust gases in good heat exchanging relation to but not in contact with the material for heating the material at times to drive off the adsorbed refrigerating fluid.

32. The method as set forth in claim 31 which further comprises, removing substantially all of said engine cooling fluid before applying the engine exhaust gases whereby the heat applied is minimized and the speed of heating is increased by avoiding the waste of heating the cooling fluid.
